Patented Nov. 2, 1976

242,166

SUPPORT FOR CAR CLEANING EQUIPMENT OR THE LIKE

Ivan J. Barber, Mississauga, Ontario, Canada, assignor to
The Allen Group Inc., Melville, N.Y.

Filed June 12, 1975, Ser. No. 586,294

Term of patent 14 years

Int. Cl. D15—05

U.S. Cl. D15—56

Fig. 1

Fig. 2

Fig. 6

Fig. 3

Fig. 5

Fig. 4

FIG. 1 is a perspective view of a support for car cleaning equipment according to my new design;

FIG. 2 is a right elevational view thereof;

FIG. 3 is a left elevational view thereof;

FIG. 4 is a top plan view thereof;

FIG. 5 is a left end view thereof; and

FIG. 6 is a right end view thereof.

I claim:

The ornamental design for a support for car cleaning equipment or the like, as shown and described.
